UNITED STATES PATENT OFFICE

2,611,572

DISPLAY DEVICE

John La Rocca, Valley Stream, N. Y., assignor to
 Pioneer Mounting & Finishing Co., Inc., New
 York, N. Y., a corporation of New York

Application June 22, 1948, Serial No. 34,413

2 Claims. (Cl. 248—174)

1

This invention is an improvement in exhibiting devices; and more particularly an exhibiting device of sheet material shaped to present samples of merchandise and advertising matter for purposes of display.

An important object of the invention is to provide an exhibiting device of sheet material comprising hinged members which can be folded against other portions, so that the device can be flattened or collapsed for storage or shipment, and which are associated with retaining elements that automatically act to maintain all parts in proper position when the device is set up complete.

Another object is to provide a display stand having movable members to be manipulated to give the stand its predetermined final configuration, and bearing tongues that are so mounted with respect to said members that the tongues at once, without further manipulation, swing into engagement with a part of the device or other rigid surface, and thus the stand is put into readiness for its intended use.

Other objects and advantages are made clear in the following description and the novel features are pointed out in the claims. But this disclosure is explanatory only, and presents only the best forms of my improvement now known to me; and I reserve the right to make changes in various details without necessarily deviating from the general design characterizing the invention or omitting any of the essential parts.

On the drawings,

Figure 1 is a rear view in perspective of an exhibiting device according to my invention;

Figure 2 is a horizontal section on line 2—2 of Figure 1;

Figure 3 is a rear elevation thereof with the parts in collapsed position;

Figure 4 is a front view in perspective of another embodiment of my invention;

Figure 5 is a vertical section on line 5—5 of Figure 4;

Figure 6 is a front elevation of said other embodiment with all parts folded together;

Figure 7 is a view similar to Figure 1 showing another embodiment of the invention;

Figure 8 is a transverse section on line 8—8 of Figure 7;

Figure 9 is a rear view of the stand of Figure 7 with all parts collapsed;

Figure 10 is a front view similar to Figure 4 of a further embodiment of my invention as it appears when set up;

Figure 11 shows the same embodiment collapsed;

2

Figures 12 and 13 are views similar to Figures 10 and 11 respectively showing an additional form of display stand;

Figures 14 and 15 are sections along lines 5 14—14 and 15—15 respectively on Figures 12 and 10; and

Figures 16 and 17 are respectively a rear elevation and a horizontal section of another form of my invention.

The exhibiting device has the form of a display stand, and it can be conveniently fashioned out of cardboard or other sheet material cut and scored for bending into desired form or to be folded flat to be stored or packed for shipment.

15 In Figures 1, 2 and 3 the stand comprises a flat piece of cardboard or the like, of any required outline, as shown at 1, to serve as a display panel. On its front face, this panel can bear pictures, printing, symbols and other advertising matter.

20 and to the rear face is secured a supporting part 2, glued or otherwise attached. This member has a longitudinal central section 3 between parallel longitudinal score lines 4, between which

25 and the side edges are triangular or wing members 5. When these side sections are bent along the score lines 4 away from the panel 1, the stand can be placed on any horizontal surface and the sections 5 will act as props to hold the panel 1 in upright position. The piece 2 is at-

30 tached to the panel over the face of the middle portion 3 of the entire member 2 between the lines 4, and the sections 5 are widest along the edges which serve as the bottoms of the props.

These edges can be inclined at such an angle to the lines 4 that when the stand is set up, the panel is not vertical but tilts slightly backward.

Just below the middle of the length, or height, of the member 2, each side thereof has two transverse or horizontal parallel cuts 6. These

40 cuts lie mostly in the sections 5, but they extend across the score lines 4 for a short distance. All four cuts 6 are of the same length. The ends thereof are united by score lines 7 in the middle part 3. These two score lines 7, joining the ends

45 of the cuts 6 near the intersections of these cuts with the lines 4 and lying between these lines 4, are relatively close together; being separated by a space less than the distance between the score lines 4. The other two score lines 8 uniting the more remote ends of the cuts 6 are much farther apart, lying within the sections 5, near their outer lateral edges.

These cuts 6 and score lines 7 and 8 define two small rectangular sections 9 in the member 2, one cooperating with each prop section 5. Each section 9 is cut through in the middle to

make a transverse or horizontal tongue 10, these tongues extending towards each other. They remain connected to the sections 9 at one end, which may be termed the root end; and the extremities of the sides of the tongues at the root ends are united to the cuts 6 by score lines 11 parallel to the lines 4 and 8. The small sections 9 can therefore be bent somewhat along these lines 11. The score lines 4 are interrupted by the sections 9 and do not cross these sections.

It will now be clear that the distance between each pair of score lines 7 and 8 is greater when the sections 5 are laid flat against the panel 1 than when the sections 5 are swung away from the panel by bending them along the score lines 4. Therefore as the sections 5 are turned into position to hold the panel upright, when the device is set up on a horizontal surface, the shortening of the distance between each pair of lines 7 and 8 inevitably causes the sections 9 to bend along the lines 11. The parts of the sections 9 between the lines 7 and 11, except the tongues 10, come to intersect the planes of the sections 5, bending around the lines 7. The remaining parts of the sections 9 including the tongues 10 are swung outward about the lines 8. The tongues 10, being rigidly attached to these sections 9 along the root ends, are then forced into the positions shown in Figures 1 and 2. Their outer or free ends thus come into abutting engagement with the back of the panel, making frictional contact therewith. This action takes place automatically, and the stiffness of the sections 5 will press the tongues against the panel and hold them fast. The sections 5 are now maintained in position to act as props to support the panel 1, and the stand will not fall till the tongues are released by one's fingers and pushed back towards the lines 4. The rectangular sections 9 will then gradually straighten out and come back towards registry with the faces of the sections 5 and 3. When the member 2 is completely flattened again, the sections 9 will once more lie in the plane thereof, and the stand can be stored or set up again. No fastening means on the tongues are needed.

Hence the device is very easy to set up, and to do this nothing more is required than to bend back the sections 5. The manipulation is quick and certain in its results.

In the embodiment presented in Figures 4, 5 and 6, a base or bottom section 12 is connected to a hinged member 13 serving as the display panel, which can be turned up or down along a score line 14 at one edge. This panel is joined along the edge 14 to a horizontal section 15 which makes contact with the upper face of the base along the front thereof, and is affixed thereto as by gluing.

In the panel are vertical cuts 16 running from the section 15 into the panel 13, two cuts 16 being employed. The ends of the cuts of each pair are united by transverse score lines 17 in the sections 15 and 18 in the panel 13 near its free or upper edge; and the cuts and score lines enclose two rectangular sections 19 which begin below the top or outer end of the display panel and extend across the score line 14 into proximity to the front edge of the section 15 on the base 12. Each section 19 is also cut through to outline tongues 20, which extend in a direction away from the outer or free end of the panel towards the line 14. The attached or root ends of the tongues 20 are joined to the cuts 16 by score lines 21 in section 19, the tongues of course being rigid with respect to said sections.

When this blank is collapsed, the distance between each pair of lines 17 and 18 is greater than the distance between said lines when the panel is set up. Hence the movement of the panel toward upright position causes bending of the sections 19 about the score lines 21, as illustrated in Figures 4 and 5; but the tongues 20 do not bend. They swing back of themselves with the portions of the sections 19 between the lines 21 and 18, about the upper score lines 18 and come into contact with the stationary base 12. The panel is thus supported because the frictional contact of the free ends of the tongues 20 with the base 12 will prevent slipping. The remaining areas 5 of the face of the panel 3 shown at 22, 23, 24 and 25 can bear advertising matter; and packages of merchandise can be inserted into the recesses or openings left by the tongues 20. The section 15, except the lower ends of the sections 19 is of course glued or otherwise secured to the base 12. The openings left by the tongues are indicated at 26.

The operation of this form is thus similar to the operation of the first form described above and gives the same result.

In Figures 7, 8 and 9 the stand is similar to the stand shown in Figures 1, 2 and 3 but the middle portion 3' between the vertical score lines 4a is narrower. Between the creases 4a and their lateral edges the legs or props 5 have additional longitudinal score lines 8a. Both the creases 4a and 8a are interrupted near the middle of the member 2. To this end the member 2 has transverse cuts 6 as before to define sections 9'. Each 30 of the two sections 9' has one end between the extremities of the lines 6 connected to the member 2 along a crease in line with the adjacent crease or score line 8a; and the other end is joined to the middle portion 3' of the member 2 along score lines 7 which are relatively close together. Above and below the sections 9' are transverse cuts 6' parallel to the cuts 6 and joining the adjacent ends of the score lines 4a and 8a, both of which terminate at these cuts 6', but being continued therefrom to both the top and bottom of the member 2. Each cut 6' is joined to the adjacent cut 6 by a vertical cut 11', which is close to, but just out of line with the adjacent crease 4a, being placed a little towards the score lines 8a. The cuts 6, 6' and 11' thus define four tongues 10', two at each side one above the other.

When the wings 5 are turned away from the panel or display member 1' around both the score lines 4a and 8a the rigid tongues 10' turn towards the back of the panel, make contact with it and are pressed against the latter. Thus they secure the wings 5 in supporting position. The stand can easily be folded and collapsed. If the wings 5 are wide and overlap the sides of the panel 1, and the distance between the score lines 8a is greater, the wings 5 can be folded flat against the middle part 3' of the member 3 by bending them along the lines 8a.

It will be noticed in connection with the design 65 of Figures 7, 8 and 9, that the swinging of the parts 5 away from the panel 1 necessarily causes some bending of the parts 5 around the score lines 8a and as soon as the parts are bent in this manner the tongues 10' stick out in the planes of the parts 5 which extend away from the panel and thus project into engagement with the back of the panel.

Figures 10, 11 and 15 present another design 70 of exhibiting device in the form of a display stand of sheet material having one layer to make a base

12' and a panel or display member 13' to be supported upon this base. The panel 13' is in one piece with a section 15' that is made fast, as by gluing to the front of the base 12', and the panel is hinged to the section 15'. In the middle the panel has an upright opening 26' which is widened at the lower portion; the sides along this lower portion being concave; and the section 15' has a rounded projection 15a which lies in the lower portion of the opening 26' when the parts of this stand are folded together.

At each side of the projection 15' is a transverse score line 17a, and in the lower part of the panel 13' are alined transverse score lines 18a. The inner ends of these score lines are connected to the curved edges of the opening 26' and the outer ends by cuts 16', to mark off sections 19a at each side of the middle opening 26'.

The cuts 16' extend forward past the score lines 17a into the section 15' and their front ends are connected to transverse score lines 17b that run to the side edges of the section 15 of the base. These score lines 17b and cuts 16' mark off connector strips 19b that are joined to the panel 13' along transverse score lines 18b which begin at the score lines 16' at points adjacent the score lines 18a and extend towards the side edges of the panel 13'; terminating in L-shaped cuts 16a that make part of the side edges of the connectors or sections 19b and run straight through the side edges of said connectors. The cuts 16a outline projections or tongues 20' rigid with the panel 13' at both sides. The projections 20' are free at one end and when the panel is turned up the sections 19a and 19b are into inclined position, bending around the score lines 17a and 18a, and 17b and 18b. The projections 20' then extend down and their lower ends enter openings 27 in the base to lock the main part of the panel 13' in display position. The panel, the front 15' of the base 12', the sections 19a, and other parts can be printed with advertising matter and the article can be inserted in the lower part of the opening 26' to rest upon the projection 15a. This device is set up, when the parts are flat, as shown in Figure 11, by swinging the main part of the panel 13 forward, lifting the sections 19a and 19b, and inserting the projections 20' into the apertures 27.

In the additional modification shown in Figures 12, 13 and 14, the base 12a has another sheet of material secured thereto along one terminal portion, as indicated at 15a, and the remainder of the sheet presents a panel 13a to be held up in visible position. The panel or display member 13a has transverse score lines 14a extending from the sides towards the center, but terminating short of the center, and below these lines 14a are other score lines of the same length 17c. The inner ends of the score lines 14a and 17c are connected by longitudinal cuts 16a. These score lines and cuts enclose sections or connectors 19c. Between the sections 19c and at the center of the lower part of the stand is a section or connector 19d enclosed between cuts 16b, which are parallel to the cuts 16c, and score lines, one of which is in line with the score lines 14a, and the other 17d being a little closer to the front of the article than the line 17c. Thus the section 19d is outlined; and between the section 19d and the side

sections 19c are tongues 20" cut free along their sides by the lines 16c and 16b, and also cut free at their lower ends along the lines 28. The lower ends of these tongues 20" have wide projections 5 so that when the panel 13a is turned up, the sections 19c and 19d are lifted into inclined position; while the tongues 20" remain rigid with the panel 13a and swing back until the projections 28 at their lower ends enter the apertures 27. The panel 13a is then held up in the position shown in Figures 12 and 14.

In the modification of Figures 16 and 17 which is similar to the invention as illustrated in Figures 1, 2 and 3, the cuts 10a outlining each tongue 10 are continued along both sides past the free end of the tongue into the middle section 3. Joining each cut 10a with one of cuts 6 in the section 3 is a short score line 7a. Hence there is a small projection 10b in the middle section 3 between the cuts 10a which is rigid with the section 3. Also the two rectangular sections 9 each have another score line 8a parallel and close to the line 8. This structure is easier and surer to manipulate and can be set up to better advantage, 15 because, where the members 5 are swung out as shown in Figure 17, the parts 9' of the sections 9 move more freely, swinging about the score lines 7a as hinges, and the part 10b of the section 3 between them does not bend at all and does not hinder the parts 9'. Also the extra creases 8a enable each tongue 10 to move more readily into place to prop the parts 2 against the panel 1.

Having described my invention, what I believe to be new is:

- 35 1. A display stand comprising a base and a panel to stand upright on the base, connector sections hinged to the panel and to the base at each side of the panel and base, said panel having an opening between the said connector sections, a connector strip hinged to said base and to said panel at the outer side of each connector section, and a tongue rigid with the panel and extending from the lower part thereof adjacent each connector strip to hold the panel upright on said base.
- 40 2. A display stand comprising a base and a panel to stand upright on the base, connector sections hinged to the panel and to the base at each side of the panel and base, said panel having an opening between the said connector sections, a connector strip hinged to said base and to said panel at the outer side of each connector section and a tongue rigid with the panel and extending from the lower part thereof adjacent each connector strip to hold the panel upright on said base.
- 45 3. A display stand comprising a base and a panel to stand upright on the base, connector sections hinged to the panel and to the base at each side of the panel and base, said panel having an opening between the said connector sections, a connector strip hinged to said base and to said panel at the outer side of each connector section and a tongue rigid with the panel and extending from the lower part thereof adjacent each connector strip to hold the panel upright on said base, said connector sections and said connector strips, when the panel is raised, extending forward at an inclination from the panel to the base, the inclination of said sections being greater than the inclination of said strips.
- 50 4. A display stand comprising a base and a panel to stand upright on the base, connector sections hinged to the panel and to the base at each side of the panel and base, said panel having an opening between the said connector sections, a connector strip hinged to said base and to said panel at the outer side of each connector section and a tongue rigid with the panel and extending from the lower part thereof adjacent each connector strip to hold the panel upright on said base, said connector sections and said connector strips, when the panel is raised, extending forward at an inclination from the panel to the base, the inclination of said sections being greater than the inclination of said strips.
- 55 5. A display stand comprising a base and a panel to stand upright on the base, connector sections hinged to the panel and to the base at each side of the panel and base, said panel having an opening between the said connector sections, a connector strip hinged to said base and to said panel at the outer side of each connector section and a tongue rigid with the panel and extending from the lower part thereof adjacent each connector strip to hold the panel upright on said base, said connector sections and said connector strips, when the panel is raised, extending forward at an inclination from the panel to the base, the inclination of said sections being greater than the inclination of said strips.
- 60 6. A display stand comprising a base and a panel to stand upright on the base, connector sections hinged to the panel and to the base at each side of the panel and base, said panel having an opening between the said connector sections, a connector strip hinged to said base and to said panel at the outer side of each connector section and a tongue rigid with the panel and extending from the lower part thereof adjacent each connector strip to hold the panel upright on said base, said connector sections and said connector strips, when the panel is raised, extending forward at an inclination from the panel to the base, the inclination of said sections being greater than the inclination of said strips.
